UNITED STATES PATENT OFFICE.

FRANK J. LIGHTBODY, OF CAMBRIDGE, MASSACHUSETTS, ASSIGNOR TO CAMBRIDGE NOVELTY COMPANY, OF CAMBRIDGE, MASSACHUSETTS, A CORPORATION OF MASSACHUSETTS.

DESIGN FOR A METAL MESH FABRIC.

40,388.

Specification for Design.

Patented Dec. 7, 1909.

Application filed October 13, 1909. Serial No. 522,501. Term of patent 3½ years.

To all whom it may concern:

Be it known that I, FRANK J. LIGHTBODY, of Cambridge, in the county of Middlesex and State of Massachusetts, have invented a new, original, and ornamental Design for Metal Mesh Fabrics, of which the following is a specification, reference being had to the accompanying drawing, forming part thereof.

The figure is a plan view of a piece of

metal mesh fabric, showing my new design.

I claim:

The ornamental design for a metal mesh fabric, as shown.

FRANK J. LIGHTBODY.
